Attorney

UNITED STATES PATENT OFFICE.

FRANK ZELKO, OF JOLIET, ILLINOIS.

WALL SLAB.

Application filed June 14, 1922. Serial No. 563,181.

To all whom it may concern:

Be it known that FRANK ZELKO, a citizen of the United States of America, residing at Joliet, in the county of Will and State 5 of Illinois, has invented new and useful Improvements in Wall Slabs, of which the following is a specification.

The object of the invention is to provide a sheathing or wall slab for use as a 10 surfacing means for the exterior walls of buildings particularly when the original sheathing has become ineffective to exclude air and moisture, and which may be applied either to the studding directly or to the 15 exterior surface of the weather boarding or other wall covering through which securing means may be driven for securing an anchorage to the frame work or studding of the building; and with this object in view 20 the invention consists in a construction and combination of parts of which a preferred embodiment is shown in the accompanying drawings, wherein:—

Figure 1 is a side view of a portion of a 25 building wall provided with a sheathing consisting of slabs constructed in accordance with the invention.

Figure 2 is a detail view of one of the 30 slabs.

Figure 3 is a similar view showing the reverse side thereof.

Figure 4 is a transverse sectional view 35 on the plane indicated by the line 4—4 of Figure 1.

The slab is provided with a body portion 10 of molded cement and sand or the equivalent thereof having the characteristics of the ordinary building blocks and a thickness suitable for application to the exterior surface of 40 a building without producing a clumsy or awkward appearance. For example the slab may be of a thickness of an inch or an inch and an eighth or more or less, an area of for example 8x16 inches. At its upper edge 45 or at one side edge it is provided with attaching ears 11 and 12 and at its lower edge with anchoring ears 13 extending respectively beyond said opposite side edges or said upper and lower edges, with the 50 outer faces of the anchoring ears flush with the rear surface of the slab body, and with the rear surfaces of the attaching ears flush with the rear surface of the slab body. The

terminal attaching ears 11 are preferably arranged near the end edges of the slab, and as 55 indicated in the drawing the anchoring ears 13 may be formed as parts of the same strips 14 as the said attaching ears, said strips being embedded in and thus securely incorporated with the body of the slab, but with the 60 anchoring ears 13 spaced at a shorter interval or closer together than the attaching ears 11 so that the anchoring ears of one slab are adapted to pass behind the upper edge of the slab in the next lower series or 65 course between the attaching ears thereof or as indicated in Figure 1 the slab in an upper course may be arranged in break-joint relation with adjoining slabs in the next lower course with the anchoring ears of 70 the former disposed on opposite sides of the attaching ears of the adjoining slabs in the lower course and with the intermediate attaching ear 12 of the first-named slab in position for attachment to the studding 15. 75 The attaching ears are adapted to be secured either to the weather boarding if the sheathing is placed thereover, or directly to the studding or framework of the building, or attaching means such as nails or the equivalents thereof may be driven entirely through 80 the weather boarding and into the studding, this obviously being the preferable course, with the anchoring ears of each course interlocked with the upper edges of the slabs 85 in the next lower course so that each slab requires fastening only at its upper edge to afford a weather excluding protection for the wall.

Having described the invention, what is 90 claimed as new and useful is:—

A sheathing slab having a body portion of cement, and strips carried by the body portion and disposed in downwardly divergent relation, said strips being embedded in the 95 body portion and terminally projecting beyond the upper and lower edges to provide, respectively, attaching and anchoring means of which the former have their rear faces flush with the rear face of the slab and the latter have their front faces flush with the rear face of the slab.

In testimony whereof he affixes his signature.

FRANK ZELKO,
